DENTAL LAMP

Walter D. Teague, Annandale, N.J., and Norman E. Lauterbach, Pittsford, N.Y., assignors to Ritter Company, Inc., Rochester, N.Y., a corporation of Delaware

Filed Feb. 24, 1958, Ser. No. 49,760

Term of patent 14 years

(Cl. D48—20)

FIG. 3.

Fig. 1 is a side elevational view of a dental lamp showing our new design;

Fig. 2 is a top plan view thereof;

Fig. 3 is a front elevational view thereof; and

Fig. 4 is a perspective view thereof, with the bracket arm omitted for conveniences of illustration.

We claim:

The ornamental design for a dental lamp, substantially as shown.
